AUTOMATIC MACHINE

Fritz Schulte, Berlin-Halensee, Germany

Application October 13, 1932, Serial No. 637,661
In Germany June 1, 1931

1 Claim. (Cl. 194—58)

Automatic machines for small packages of goods such as matches which are intended to be placed on a table can only be made of small dimensions as they need to be portable. The problem therefore is to make the action for releasing the packages after insertion of a coin as well as the store of goods and the space for receiving the money as compact as possible while ensuring satisfactory action and protection against theft.

This problem is solved by the invention in a simple manner in that the withdrawal of the package from the stock is effected by means of a slide which after being released by the inserted coin engages in its end position at the rear of the uppermost package of the stock and ejects it at its return while at the same time holding back by means of its driver the pile of packages and preventing them from being raised. It is, therefore, impossible for the packages to be removed from the casing of the automatic machine improperly because the pile is not accessible. At the same time a comparatively small casing is used because the packages can be moved directly from the pile to a track from which they pass to the delivery slot. It is therefore not necessary first to move the packages forwards and then to guide them on to a track. The latter may be attached directly to the shaft. For receiving the money a small space is sufficient, which is only a few millimetres broader than a coin since in such automatic machines as a rule only a small number of packages are inserted at one time. In addition, provision is made for closing the coin slot after the last package has been withdrawn and also for locking the movement of the slide itself in certain positions so that, for example, when a coin is inserted the slide cannot be moved back when it has been drawn out a certain distance. The slide must be drawn out to its end position before the release of the package is possible.

According to further features of the invention the coin tester is so arranged that it rejects coins or discs which are wrapped in foil and also a magnet is provided which prevents magnetic coins setting the machine in motion. The magnetic testing device has the advantage that it cannot be put out of action by drawing away the coin by means of a wire or the like inserted through the slot. By this invention it has been made possible for the first time to provide a magnetic coin tester in such small automatic machines.

The accompanying drawings illustrate one constructional example of the invention.

Fig. 1 is a side elevation and

Fig. 2 a vertical section on the line 2—2 of Fig. 3.

Fig. 3 a horizontal section on the line 3—3 of Fig. 2.

Fig. 4 is an elevation of a detail.

Fig. 4^a is a fragmentary horizontal sectional view through the casing of the machine showing the coin releasing member in detail.

Fig. 5 shows the automatic machine combined with ash-trays in side elevation.

Fig. 6 is a plan corresponding to Fig. 5.

Fig. 7 is a part section through the casing 15 with a side elevation of the coin tester and the co-operating parts in another constructional example.

Fig. 8 is a horizontal section on the line 8—8 of Fig. 7, the section line 7—7 therein shows the 20 section of Fig. 7.

Fig. 9 is a view corresponding to Fig. 7 with the slide and coin tester moved forward somewhat.

Fig. 10 is a horizontal section approximately 25 on the line 10—10 of Fig. 8 turned through 180°.

Fig. 11 is a vertical section through the automatic machine with magnetic tester.

Fig. 12 is a vertical part section on the line 12—12 of Fig. 11.

Fig. 13 is a vertical part longitudinal section as in Fig. 11 with the side drawn forward.

Fig. 14 is a horizontal part section on the line 14—14 of Fig. 12.

The casing *a* (Figs. 1—6) contains the shaft *b* for a pile of packages, for example flat boxes *d* of matches. The pile rests on a pressure plate *c* which is acted on by a spring *c'* and presses the packages upwards by means of a strip *c''*. The casing *a* is closed at the top by a cover *e* 35 and an intermediate cover *e'*. Between the two covers is guided the slide *f* which by means of a handle *f'* projecting through the slot *f''* in the cover *e* is longitudinally displaceable in this slot. A second fixed handle *g* in the cover *e* 40 serves as a holder so that the handle *f'* can be displaced against the action of the spring *m* engaging between the slide *f* and the casing *a*. In its forward position in Fig. 1 the slide *f* rests with a driver *d'* on the uppermost packing *e* 45 and thereby holds the pile back. Only in its end position (Fig. 2) the driver *d'* engages over the uppermost package *d* which now, by means of the spring *c'*, is pressed against the strip *c''* on the casing *a*. The casing is recessed at *d''* 50

and thereby holds the pile back. Only in its end position (Fig. 2) the driver *d'* engages over the uppermost package *d* which now, by means of the spring *c'*, is pressed against the strip *c''* on the casing *a*. The casing is recessed at *d''* 55

so that the driver d^1 can pass through sufficient-
ly far.

Between the cover e and the slide f a cover plate g^1 is interposed which in the end positions of the slide f moves with it and always covers the slot f'' in the cover e so that nothing can fall through it into the interior of the casing.

The slide f carries the coin tester h which consists of a longitudinal wall with transverse webs h^1 and h'' running in the shape of wedges. 10 Between these lies the coin i inserted through the slot m'' (Fig. 3) into a lateral shaft b'' which is divided off in the casing a by the partition m^1 , an arm k is mounted at k' which is moved backwardly by a spring k'' acting on its end. 15 This arm k rests on the uppermost transverse web h'' and provided with a tooth l made in the shape of a ratchet so that a locking surface l' is obtained. The side wall of the coin tester h is broken at q so that in the aperture a wedge-like stop l'' on the casing can pass through in the end position of the slide f . In 20 the space between the two covers e and e' there is also arranged a bolt n which at the end n'' is bent over in the form of a hook and usually rests in its lower position so as to leave open the path for the slide f until the latter can abut against the casing wall with its left hand under cut end s . The slide engages by means of a 25 lateral extension s' under a coin slot m'' in the casing and is provided with a slot m^3 which uncovers the slot m'' in the return position shown in Figs. 1 and 3. The bolt n carries a pin o projecting into the shaft b and located above the stop c'' .

The mode of operation of the automatic vending machine is as follows: A coin inserted in the slot m'' falls into the coin tester h and remains between its webs h^1 and h'' , as shown in Figs. 1-4. If now the two handles g and f^1 are 40 relatively displaced, the slide f moves into the end position shown in Fig. 2. Then the arm k , on account of its tooth l being lifted by the coin i , is raised together with the locking tooth l' to such an extent that the coin tester h with its 45 upper web h'' can slide unhindered below the arm k . If it is attempted to move the two handles f^1 and g without inserting a coin, the upper web h'' impinges against the tooth l' and the forward movement of the slide f is prevented. 50 After the insertion of a coin, however, the two handles f^1 and g can be relatively moved so far that the slide f with its driver d^1 moves into the recess d'' in the wall of the casing. The spring c^1 now presses the pile of packages upwards and the uppermost package d bears from below against the strip o^1 and thus comes above the upper edge of the guiding track b^1 which leads to the withdrawal slot a'' . If now the handle f^1 is released the spring m draws the 55 slide f back and its driver d^1 moves the uppermost package d over the guiding track b^1 on which it slides out. Shortly before the end position of the forward stroke of the slide f the wedge-shaped stop l'' (Fig. 4a) presses the coin i out of the coin tester h so that it now falls into the shaft b'' .

This wedge-shaped stop l'' is so arranged that it ejects the coin i from the coin tester h before the driver d^1 engages the uppermost package d in order to prevent the slide with the coin being drawn back again and a package being at the same time moved forwards.

When the last package is removed the stop c'' 70 impinges against the pin o and the spring c^1

thereby presses the bolt n upwards whereby its hook n'' lies in front of the front edge s of the slide f . The latter cannot now complete its forward stroke but is held back somewhat. The strip s^1 below the slot m'' therefore does not move right back and the insertion of the coin is prevented. 5

With the casing a of such a vending machine, ashtrays t may of course be combined in a known manner. These preferably consist of an artificial 10 material and not of metal.

In the constructional example shown in Figs. 7-10 the arrangement in general is similar to that described above. Under the cover e of the casing a is guided the slide f which carries the coin tester h which slides laterally below the coin slot m'' . This has pairs of guiding pins h^1 and h'' . The upper pair h^1 allows a coin of correct size to fall while the lower pair h'' holds the coin back so that when the slide f is moved in 20 the direction of the arrow it can lift the release pawl. The front pin h^1 then slides freely under the pawl k and allows the slide f to be moved to the end position so that by means of its pin d^1 it can engage a package d and eject it. Below 25 the coin slot m'' there are arranged on the coin tester h resilient tongues u^1 which, for example, are mounted on or stamped out of a disc u of resilient sheet metal. They project into the path of the coin so that the coin has to be pressed between the tongues u^1 with a light pressure. In 30 this way foil which has been wrapped round a coin of small value is scratched off and the coin drops through between the pair of pins h'' and cannot cause the pawl k to be released. In the 35 same way cardboard discs which are inserted are damaged at the circumference.

A third resilient tongue v^1 is arranged on a spring arm v secured to the casing. It is disposed somewhat upwardly and thus engages with 40 its tongue v^1 in the initial position of the slide f under the front web h'' . The coin tester h has in its lower edge a notch v'' which forms a locking tooth. When a coin of the correct size is inserted the tongue v^1 slides past the coin which 45 overcomes the pressure of the spring arm v because it comes to lie under the point of the pawl k during the movement of the slide f (Fig. 9). The tongue v^1 then does not come in engagement with the notch v'' . If, on the other hand, a card 50 disc is inserted, the tongue v^1 is pressed into the disc and also engages in the notch v'' so that the slide f is prevented from further movement.

For limiting the swinging movement of the pawl k which is acted on by its spring k'' there is 55 a further pin w on the coin tester h which prevents the pawl k being lifted from without by means of a flat article such as a paper strip as long as the slide f has not been moved forward to any great extent. Another pin w^1 on the pawl k bears against a strip x on an inner wall x^1 of the casing a . In this way the pawl k is prevented from swinging too far downwards.

A further improvement consists finally in that the pressure plate c which forces the packages d 60 upwards against the slide f is perforated at y . Through this perforation a spring arm c'' can project with its erect pin y' as soon as the last package is ejected. This spring arm, by means of the pin y^1 , then forces the member n upwards 65 which prevents the slide f being moved back to its end position in order to close the slot m'' for 70 the coins.

The magnetic coin testing device is shown especially in Figs. 11, 12 and 14. In the casing 75

a there is mounted at z^1 a swinging arm z^2 which carries a magnet z . The distance through which the arm z^2 and the magnet z can swing is so limited that it lies closely in front of the coin tester h so that an inserted coin i can slide past the magnet z (Fig. 12). If the coin i is magnetic it is attracted and held by the magnet z . The swinging arm z^2 carries a nose 22 which bears against a wedge surface 21 of the slide f . On the casing a is also placed a scraper 20 which preferably consists of prongs embracing the magnet z . When a magnetic coin is inserted it is attracted by the magnet z and when the slide f is moved a little is drawn out of the coin tester h . Then the wedge surface 21 on the slide f presses the nose 22 with the arm z^2 and the magnet z so far back that the coin i is withdrawn from the coin tester h . When the coin tester h is further moved back by means of its nose 22 the coin i lies against the scraper 20 and then falls in the coin box and is not returned.

Such a magnetic coin tester can be built into small automatic machines which has not hitherto been possible because the usual magnetic coin testers had to be constructed in the path of the coin and also make it possible to remove the coin from without and require the coin shaft to be divided for releasing the coins.

The cover wall e^1 lying at a distance below a cover e is at one point below the slide f formed with a depression 23 having conical side walls in which rests a ball 24 . Further, there is movably arranged on the covering wall e^1 at $25'$ a locking bolt 25 which consists, for example, of a rigid arm of sheet metal. The slide f carries a pin 26 of such a height that when the machine is in the erect position it can slide freely over the locking bolt 25 . As soon as the machine is placed in an oblique position or laid down on one side or turned upside down, the ball 24 , is moved by gravity and on account of its weight, depresses the bolt 25 in the neighbourhood of the pin 26 .

The slide f can therefore not be moved even when a correct coin is inserted. In order to avoid dirt collecting in the conical depression 23 it can be perforated at the lowest point at $23'$.

If the slide f is moved in the proper manner so that its driver d^1 engages over the uppermost package d , the outlet opening above the oblique guiding track b^1 will be accessible at its upper end through the slot a^2 for a knife blade or a similar tool so that the next package could be drawn out. In order to prevent this the slide f also carries a closing wall 27 which reaches down to the oblique wall b^1 and thus prevents access to the packages.

In order also to ensure the closing of the slot 15 by the closing plate n in each case the spring arm y^1 serving for actuating the closing plate n is pivotally mounted by means of pins y^2 and is acted on by a separate spring 30 (Figs. 11 and 13). When the last package has been removed 20 the spring 30 presses the spring arm y^1 upwards through the slot y of the pressure plate c so that the arm y^1 can lift the closing plate n somewhat whereby its hooks n^2 come near to the slide f .

What I claim is:

An automatic vending machine, comprising a casing having a coin slot, a compartment for the stack of articles, an inclined guiding track for the articles in front of said compartment, a spring, a slide guided above said track and said compartment, and movable against said spring, a member on said slide arranged to hold down the stack against elastic pressure and to engage in its tensioned position behind the uppermost article, a coin receiving and testing device connected to the slide and arranged below the coin slot in said casing, said device being guided by the side of said stack compartment and said guiding track, and means to block the slide and 35 adapted to be released by a coin.

FRITZ SCHULTE.
